SHEET FEEDING AND FORWARDING
MECHANISM

Charles F. Pflanze, University City, Mo.

Application October 31, 1936, Serial No. 108,543
Renewed July 5, 1938

8 Claims. (Cl. 271—1)

My invention relates generally to sheet feeding and forwarding mechanisms, and more specifically to the alining means embodied in said invention which utilizes air suction or vacuum in the control of and advancing of the blanks to the scoring and folding or printing mechanism. When the air suction by means of which the blank is advanced is cut off, the blank becomes immediately inert with no tendency to continue in motion. With the air suction feeding means, the instant the air suction or vacuum is cut off the blank becomes inert instantaneously. By thus advancing each blank it may be accurately alined both longitudinally and transversely before it is advanced to the scoring and folding or printing mechanism.

My invention consists broadly in a sheet feeding and forwarding mechanism in which a pile of sheet material is impinged against a stop device on a feed table, and whereby the topmost sheet is lifted and advanced by a reciprocating lifting and advancing suction device over said stop device for delivery to a rotary suction member for further advancing and delivering said sheet in proper alined position to scoring, folding, or printing mechanisms in the machine to which my invention applies.

More specifically, I have illustrated and described my invention applied to an envelope-forming machine in which pregummed envelope blanks are advanced to a feed table and accumulated against a stop device in a pile consisting of a plurality of said blanks. The reciprocating lifting and advancing suction device lifts and advances the top sheet over said stop device to a rotary suction member which seizes and advances said sheet to a mechanical alining device, which accurately alines said blank, and when so alined said blank is held in such accurately alined position by a bottom suction cup while the mechanical alining members are withdrawn out of contact with said blank. The suction cup retains the blank in such accurately alined position until it is seized by the advancing cylinders associated with the scoring and forming mechanism of the envelope-forming machine. The reason I have shown my invention as applied specifically to an envelope-forming machine is the necessity of re-aligning the blanks after they leave the accumulated pile, where they may have been imperfectly alined. The mechanical alining device is old in envelope-forming machines, but so far as I am aware I am the first to provide a reciprocating lifting and advancing suction device associated with a rotary suction member for seizing each

blank as it is lifted and advanced by said reciprocating lifting and advancing suction device for further advancement to said mechanical alining members, while each blank is retained by each of said suction devices in the alined position, both longitudinally and transversely, which it occupied in the accumulated pile on the feed table. In the specific illustration herein shown and described, I have shown the additional feature of the bottom suction cup for holding each blank in the exact alined position secured by the mechanical alining members and pending the seizure and further advancement of each blank by the rotating cylinders associated with the scoring and folding mechanism of the envelope-forming machine. However, I do not wish to have my invention specifically limited to envelope-forming machines, as this is merely one application of such invention.

In machines of this character handling irregularly shaped material, such as envelope blanks, which are to be fed at any spaced position for pre-gumming the open flap and carried by means of forwarding belts, chains, or similar devices for the purpose of pre-drying the gum and then being converted into made-up envelopes, it has been noted through past experiences that, owing to the stretching of these chains and belts and irregularity in the spacing it has been difficult to present these single blanks to the folding mechanism in precise alined relationship.

To overcome this distinct disadvantage, I have proceeded to arrest these blanks at a predetermined point and have introduced a reciprocating lifting and advancing sucker to bring the top sheet of such arrested pile within the air of a rotary air vacuum device which has the property of forwarding the top sheet to an exact point and arresting its forward movement within the range of mechanical alining means, allowing for much more perfect alinement with the scoring mechanism than has heretofore been accomplished. It will be easily understood that through the arresting motion an accumulation of more than one blank in this predetermined, arrested position is possible, and it is obvious that this will overcome any lack of synchronism between the pre-gumming apparatus and the folding portions of the machine. There is also provided on this arresting table racking means, so that arrested position is relative to the length of the blank and the blank's relationship to the scoring cylinder can be predetermined.

Fig. 1 is a plan view of a feed table constructed in accordance with my invention, together with

a portion of the feeding mechanism for advancing the pre-gummed envelope blanks to the feed table.

Fig. 2 is a side elevation, partly in section, of the mechanism illustrated in Fig. 1.

Fig. 3 is a view taken on line 3—3 of Fig. 2, looking in the direction of the arrows.

Fig. 4 is a cross-sectional view taken on line 4—4 of Fig. 1, looking in the direction of the arrows.

Fig. 5 is a view taken on line 5—5 of Fig. 4, looking in the direction of the arrows.

Fig. 6 is a plan view of a modification of my invention with a lifting suction roller adapted to handle window envelopes.

Fig. 7 is a side elevation, partly in section, of the mechanism illustrated in Fig. 6.

In the drawings, A and B designate the lower feed belts for advancing the pre-gummed and pre-dried envelope blanks to the feed table C in spaced relation to each other, and D are top belts for holding said blanks in spaced position on the lower belts B. The blanks have had their flaps gummed at a remote point of the machine and have traveled a sufficient distance to effect the drying of the gum before reaching the point on said machine as illustrated at the right of Figs. 1 and 2. The spacing of the blanks is generally the distance determined by the gummed portion of the flaps on each blank. The belts are driven by a suitable motor, not shown.

Mounted on the side frame E of my machine is a transverse shaft 1, on which is mounted a carriage 2 provided with a series of pressure rollers 3, which carriage is mounted on the shaft 1 approximately midway of its length by means of a rod 4, which is mounted on the shaft 1 by the bearing 5. This rod 4 is adjustable in the bearing 5 and is secured in place by the bolt 6 in said bearing. These rollers 3 bear down on the upper surface of the envelope blanks F and are adapted to maintain said blanks in position on the lower feed belts A. Mounted also on the shaft 1 between the center and the ends of said shaft are two carriages 7 on which are mounted rear rollers 8 and forward rollers 9, the rear rollers being larger in diameter than the forward rollers.

The purpose of making the forward rollers 9 of less diameter than the rear rollers 8 is to permit the forward rollers to enter marginal notches 10 provided in the flap 11 of the envelope F, so that as a plurality of envelopes are accumulated at the end of the feed table C the small diameter rollers 9 may enter said notches and serve to hold said envelopes in accumulated position. The function of the larger rear rollers 8 is to serve as presser members on the envelope blanks F. The carriages 7 are pivotally mounted on the rods 12, which in turn are secured to the shaft 1 by the bolts 13.

The carriages 2 and 7 are also pressed against the envelope blanks F by the tension springs 14, of which there are three, one for each rod 12 and 4. The spring 14 is located between a curved extension member 15 on each of the supporting members 5 and 16 mounted on the shaft 1 (see Fig. 2) and the supporting members 5 and 17 for holding the rods 4 and 12.

A plurality of envelope blanks F are first accumulated at the forward end of the feed table C, as shown in Fig. 2. The top blank is then ready to be fed into the feeding mechanism and subjected to the scoring and folding operations.

This movement will now be described.

The upper portions of the belts A pass over the feed table C, which table is supported by the frame members G by bolts 18 passing through slots 19 in said table. This permits of longitudinal adjustment of said feed table to accommodate envelopes of different depths. At the forward end of the feed table C are two upwardly extending stops 20 adapted to engage the forward portion of each envelope blank and to arrest the forward movement thereof. These stops enter 10 into marginal notches in the envelope blank, one on either side of the forward portion of said blank.

A plurality of envelope blanks assemble at this point just beyond the forward end of the feed belts A and B at the forward end of the feed table C with the forward notches in said blanks resting against the stops 20. When the requisite number of blanks has been accumulated, the feeding mechanism for advancing the blanks to 15 the vacuum-controlled alining devices is placed in operation, whereby one of the blanks F from the top of the pile is lifted and advanced while another blank is being fed to the pile of accumulated blanks at the bottom. 25

The primary feeding mechanism for lifting and advancing the top blank from the accumulated pile comprises two reciprocating sucker tubes 21, which terminate shortly above the pile of blanks F and which are attached to sections of flexible 30 hose 22 leading to a vacuum pump (not shown). These tubes are pivotally supported as at 23 by two short arms 24 carried by a transverse member 25, which is pivotally mounted in the side plates H mounted on the feed table C at either 35 side thereof.

It will be noted that the arms 24 are adjustably mounted for transverse movement in the transverse member 25 (see Fig. 1), so as to accommodate envelope blanks of different lengths. 40 The member 25 at one end is provided with an arm 26 which extends forwardly and downwardly. At the forward end of the arm 26 is a roller 27 adapted to contact with a cam 28 eccentrically mounted on a shaft 29, so that when said cam 45 is rotated the arm 26 is caused to move up and down and thus to rock the transverse member 25. The upper portion of each sucker tube 21 being secured by an arm 24 to the member 25, such arm is rocked in the arc of a circle, and as 50 the forward end of each arm 24 is pivoted to the upper end of each sucker tube 21, the sucker tube is thereby caused to move up and down as the member 25 is rocked forward and backward. The lower end of each sucker tube 21 passes 55 through a slot 31 formed in another transverse member 32, which is pivotally secured to the member 25 by the arms 33, which are also pivoted to the member 32.

The slot 31 permits of the transverse adjustment of the sucker tubes 21 for different sized envelopes. The shaft 29 is driven by a sprocket chain 34 connected to a sprocket wheel 35 mounted on a shaft 36, which in turn is driven by the sprocket chain 37 connected with the sprocket 65 wheel 38 on the shaft 39, which shaft is driven by the sprocket chain 40 leading to a suitable motor (not shown).

Fastened to the member 25 near each end thereof are two arms 41 which extend downwardly and at their lower ends are adapted to engage the member 32 to rock said member forwardly, when the member 25 is operated by the arm 26. By this rocking forward movement the sucker tubes 21 are moved forwardly and upwardly, due 75

to the fact that the ends of said tubes extend through slots 31 in said member 32. Two springs 42 are attached to the feed table C and the arm 33 for the purpose of restoring the member 25 and associated parts to the position shown in Fig. 2.

Guideway strips 43 and 44 are provided, being placed transversely across the machine and consisting of five sets which prevent vertical displacement of the envelope blanks F.

The top envelope blank in the assembled pile of blanks on the feed table C is first lifted by the sucker tubes 21 when the vacuum is created, as will be hereinafter described, and then the long arms 41 strike against the side of the member 32, which moves said member and said sucker tubes and the lifted envelope blank forwardly, clearing said blank of the stops 20. This permits the further forward movement of said blank so advanced and the precise alinement of said blank, so that it will be received by the scoring and folding mechanism in the correct position to be folded accurately, regardless of any exact alinement that may have developed up to this point.

As pointed out before, each envelope blank F is provided with four marginal notches, two on each side of the blank, in which the small rolls 9 and the stops 20 first engage. As the blank is advanced as just described, these notches are engaged by four movable members 45 and 46 which are cam-actuated to cause them to be rocked into position where they can engage said notches as the blank F is advanced, as heretofore described. The members 45 are mounted on a shaft 47 mounted transversely of the machine and adapted to be operated by the cam 48, which moves the arm 49 which rocks the shaft 47 and moves the member 45 forwardly, bringing the upward projections 50 into engagement with the rear notches in the envelope blank, which has been advanced from the pile on the feed table C. The other members 46 are operated by the cam 51 mounted on the shaft 39. The members 46 are journaled on a shaft 52 and are provided with downwardly projecting extensions 53 which have rollers 54 for engaging the cam 51. As the members 46 are rocked rearwardly, the upward projections 55 engage the forward notches in the advanced envelope blank F. By this engagement of said blank it is precisely alined for its further advancement into the scoring and folding mechanism.

To advance the envelope blank F to the alinement position just described from the point of advancement by the reciprocatory lifting and advancing suction device, a rotating, perforated cylinder 56 engages the upper surface of said blank, and simultaneously the vacuum for holding the said blank in contact with said cylinder is operated and remains in effect until said blank F has been advanced to a point where it is accurately alined and where it can be gripped by the feeding cylinders 57 and 58. The vacuum effected in the several places in my mechanism will be herein-after described.

Almost under the cylinder 56 is a suction cup 30 which exerts a suction against the lower side of the envelope blank F and prevents any tendency of said blank to get out of alinement at this point after the withdrawal of the mechanical alining members. It will be noted that the cylinder 51 is not of the same diameter throughout its circumference. The purpose of this is to permit the ready entrance of the blank F be-

tween the cylinders 57 and 58 before being seized by said cylinders.

It will also be noted that the feeding cylinder 56 has a groove 59 about its center to receive one of the guideway strips 43. The guideway strips 43 may be adjusted transversely of the machine when different sized envelope blanks are being run through the mechanism. A transverse bar 60 is mounted across the machine between the cylinder 56 and the cylinders 57 and 58. On this bar 60 are mounted the guideway strips 43 by screws 61 which pass through an elongated slot 62 in said bar.

The means for creating the suction or vacuum employed in the operation of my device will now be described. The pump for creating the suction is not shown, but it is understood it can be of any standard design and operated by electric motor or other suitable driving means. Fig. 3 shows most of the piping arrangement required. On a shaft 36 are fixed four hollow disks 64, 65, 66, and 67. The hollow disk 64 is only employed when the modification shown in Figs. 6 and 7 is used, and so it is not shown connected with the other piping in Fig. 3.

Abutting these circular disks on each side are stationary members 68, 69, 70, and 71, also disk-shaped and hollow, with extensions 72 for receiving bolts 73 to hold each unit together. The disks 64, 65, 66, and 67 rotate between these outer disks 68, 69, 70, and 71. A transverse bar 74 is mounted in the machine adjacent said disks and a pin 75 passes through said bar and is seated, one in each disk unit 68, 69, 70, and 71, to prevent the rotation of said disk units.

In the side walls of each of the disks is an opening to receive the suction pull from a pipe from the suction pump and transmit such suction pull to a pipe connected with each of the units 68, 69, 70, and 71 and leading to each of the suction devices employed in my mechanism. Unit 70 leads to the suction tubes 21. Unit 71 leads to the suction device 76 in the cylinder 56. Unit 69 leads to the suction cup 30. The cylinder 56 is a part of shaft 77, and fixed therein is the hollow, non-rotatable suction device 76 with the suction pipe 78 leading to the unit 71. As the disk 67 rotates and as the openings in the side walls therein register with openings in the adjacent side walls of the disk 71, the suction is transmitted to the suction device 76 and suction is exerted upon the upper surface of the topmost envelope blank which is being transported through my machine. When suction is exerted through the other disks 68 and 70, such suction is transmitted through the connecting suction device in each case and is exerted upon or beneath the topmost envelope blank as it travels along to the scoring and folding mechanism.

In the operation of my device, the traveling web of envelope blanks F in superposed relation with each other with the gummed flap exposed, as shown in Fig. 1, is first permitted to proceed until a desired plurality of such blanks is accumulated at the forward end of the feed table C with the forward notched edges resting against the stops 20 and the rearward notched edges engaged by the small rollers 9. At this time the feeding mechanism for alining and forwarding the blanks to the scoring and folding mechanism is set in motion. The topmost blank F is lifted by the suction tubes 21 to clear said blank of the stops 20 when the rocking motion is transmitted to said tubes, and the blank is advanced to be

subjected to the action of the alining members 45 and 46.

The rotating cylinder engages the upper surface of the blank F, which, with the suction device 78 therein, under the suction transmitted to it through the unit 71 carries said blank forwardly to the alining members 45 and 46 when the suction is terminated by the rotation of the disk 61. The forward notched portion of the envelope blank F has been contacted by the upward projections 55 on the members 46 practically simultaneously with the release of the blank from the vacuum controlled feeding cylinder 56, and said blank comes under the alining control of the members 45 and 46. The lower surface of the blank F, after being alined by the members 45 and 46, is then seized by the suction cup 38 and held by said cup until the forward flap portion of said blank can be seized by the feeding cylinders 57 and 58, the forward flap of said blank being then in position between the cylinders whereby it may be caught and advanced by the larger diameter portion of the topmost cylinder 57 contacting with the lower cylinder 58. At this time the rotation of the disk 65 has cut off the suction to the device 38, so that said blank may be advanced into the scoring and folding mechanism. I prefer to employ a relatively continuous, weak suction at this point, although I could employ a strong suction and arrange an off and on connection with the cup 38. In this manner I provide a very precise and accurate alining device for the envelope blanks F which is not influenced by any inaccuracy in the feeding means up to the accumulated pile of blanks at the forward end of the feed table.

In the modification shown in Figs. 6 and 7 the structure already described remains the same. I have added a rotary suction device to handle window envelopes.

When the modified structure illustrated in Figs. 6 and 7 is employed suction from the unit 68 is applied to a suction cylinder 79', which is perforated and which is mounted on the tubular shaft 79, which rotates about a tubular member 80 through which the suction from unit 68 is applied alternately as required to the member 81, so that the portion of the envelope blank F' just to the rear of the window 82 is lifted by the suction member 81 to clear said window 82 of the underlying blank and prevent said window from catching at one edge of the underlying envelope blank, and thus permit ready and unobstructed forward feeding of said blank. The cylinder 79' is rotated by the sprocket chain 34' passing over a sprocket wheel 83 mounted on the tubular shaft 79, and which sprocket chain also passes over sprocket wheel 35 on shaft 36, and over the sprocket wheel on shaft 28.

I claim:

1. In a sheet feeding and forwarding mechanism, a feed table, a supply of sheet material delivered to said feed table, a stop device against which said sheet material impinges, means for lifting and advancing the topmost sheet of said sheet material over and beyond said stop device, said means comprising a reciprocatory lifting and advancing suction device in combination with a rotary suction sheet advancing device, said rotary suction device being adapted to seize said sheet substantially simultaneously with the release of said sheet by said reciprocatory lifting and advancing suction device, so that said sheet will remain in exact longitudinal and transverse position during the advancing movement for presentation in such exact alined position to the

further operation of the scoring, folding, or imprinting devices of the machine.

2. In a sheet feeding and forwarding mechanism, a feed table, means for delivering a series of sheet material to said feed table in spaced relation to each other, a stop device for arresting said sheet material in an accumulative pile of a plurality of sheets, means for lifting and advancing the topmost sheet of said sheet material over and beyond said stop device, said means comprising a reciprocatory lifting and advancing suction device, a rotary suction sheet advancing device, said rotary suction device being adapted to seize said sheet substantially simultaneously with the release of said sheet by said reciprocatory lifting and advancing suction device, mechanical alining members for alining said sheet in relatively exact longitudinal and transverse position, and means for advancing said alined sheet to the scoring, folding, or imprinting devices of the machine. 20

3. In a sheet feeding and forwarding mechanism, a feed table, means for delivering a series of sheet material to said feed table in spaced relation to each other, a stop device for arresting said sheet material in an accumulative pile of a plurality of sheets, means for lifting and advancing the topmost sheet of said sheet material over and beyond said stop device, said means comprising a reciprocatory lifting and advancing suction device, a rotary suction sheet advancing device, said rotary suction device being adapted to seize said sheet substantially simultaneously with the release of said sheet by said reciprocatory lifting and advancing suction device, mechanical alining members for alining said sheet in relatively exact longitudinal and transverse position, means for holding said sheet in alined position after the withdrawal of the mechanical alining members, and means for advancing said alined sheet to the scoring, folding, or imprinting devices of the machine. 35

4. In a sheet feeding and forwarding mechanism, a feed table, means for delivering a series of envelope blanks in spaced relation to each other to said feed table, means associated with said feed table for arresting the forward movement of said blanks and thereby accumulating a plurality of said blanks in alined position at said arresting point, and means for continuing the advance of each blank to alining and folding mechanisms of the machine. 50

5. In a sheet feeding and forwarding mechanism, a feed table, means for delivering a series of envelope blanks in spaced relation to each other to said feed table, a stop device associated with said feed table for arresting the forward movement of said blanks and thereby accumulating a plurality of said blanks at said arresting point, and a reciprocatory lifting and advancing suction device for lifting and advancing the topmost arrested blank over and beyond said stop device, and a rotary suction device for seizing and advancing said sheet to alining and folding mechanisms of the machine. 60

6. In a sheet feeding and forwarding mechanism, a feed table, means for delivering a continuous series of envelope blanks in spaced relation to each other to said feed table, a stop device associated with said feed table for arresting the forward movement of said blanks and thereby accumulating a plurality of said blanks at said arresting point, a reciprocatory lifting and advancing suction device for lifting and advancing the topmost blank over and beyond said stop device, a rotary suction device for seizing and ad- 70

- vancing said blank to mechanical alining members adapted to receive and aline said blank, and means for advancing said blank from said alined position to the scoring and folding mechanisms of the machine.
- 5 7. In a sheet feeding and folding mechanism, a feed table, means for delivering a continuous series of envelope blanks in spaced relation to each other to said feed table, a stop device associated with said feed table for arresting the forward movement of said blanks and thereby accumulating a plurality of said blanks at said arresting point, a reciprocatory lifting and advancing suction device for lifting and advancing the topmost arrested blank over and beyond said 10 stop device, a rotary suction device for seizing and advancing said blank to mechanical alining members adapted to contact said blank and to aline the same, means for withdrawing said alining members out of contact with said blank, a 15 suction cup located beneath said blank for re-
- taining said blank in alined position after withdrawal of said alining members, and means for advancing said blank from said suction cup to the scoring and folding mechanisms of said machine.
8. In a sheet feeding and forwarding mechanism, a feed table, means for delivering a series of envelope blanks in spaced relation to each other to said feed table, a stop device associated with said feed table for arresting the forward movement of said blanks and thereby accumulating a plurality of said blanks at said arresting point, and a reciprocatory lifting and advancing suction device for lifting and advancing the topmost arrested blank over and beyond said stop device, a rotary suction device for seizing and advancing said sheet to alining and folding mechanisms of the machine, and adjustment means for adjusting the lifting and advancing devices longitudinally and transversely to accommodate envelope blanks of different width and depth.
- 10 15 20 CHARLES F. PFLANZE.

DISCLAIMER
